UNITED STATES PATENT OFFICE.

HEINRICH ALBERTZ, OF COLOGNE, GERMANY.

CURTAIN-HOLDER.

SPECIFICATION forming part of Letters Patent No. 787,816, dated April 18, 1905.

Application filed December 9, 1903. Serial No. 184,440.

To all whom it may concern:

Be it known that I, HEINRICH ALBERTZ, locksmith, a subject of the German Emperor, and a resident of 14 Weissgerbereckgasse, Cologne, Germany, have invented certain new and useful Improvements in Curtain-Holders, of which the following is a specification.

This invention relates to improvements in curtain-holders, and has for its object a curtain-holder in which flat pieces of iron with several bends and fastened to the curtain-frame serve to receive the curtain-poles and the wall-hooks.

On the accompanying drawings a form of construction of the device is shown in Figure 1 in a front elevation, partly in section, and in Fig. 2 in plan view. Fig. 3 shows, on an enlarged scale, a detail, partly in front view, partly in section, while Fig. 4 shows the same in side view.

Similar letters refer to similar parts throughout the several views.

To the lateral parts *a'* of the curtain-frame *a* are fastened flat pieces of iron *b*, serving to receive the curtain-poles and the wall-hooks. Each iron is provided with an eye *b'*, by means of which the iron and the curtain-frame can be hung upon the wall-hooks *c*. The iron *b* carries a part *b'*, bent at a right angle, and the latter an arm *b''*, bent at a right angle so as to extend parallel to the part *b*. In the arms *b''* of each iron the curtain-poles *g* are journaled with their ends, for which purpose these arms are provided with slits *b'''*, into which the curtain-poles are placed from above. The arms *b''* carry flaps *b''''*, bent at a right angle and serving to receive the bolts *f*, which rotate in their bearings and over which pass the cords *h* for opening and closing the curtain *n*.

Above the curtain-poles *g* are inserted through the parts *b''* the pins *i* at a right angle to the direction of the curtain-poles, the ends *i'* and *i''* of the pins *i* being bent in order to prevent the falling out of the pins. In order that the pins, with their bent ends *i'*, can be inserted through the parts *b''*, the latter are provided with horizontal slits *b''''*, Fig. 3, so

that after inserting the pins and turning the same the bent ends *i''* extend vertically. 50

Along the curtain-poles *g* move the curtain-rings *m m' m''*, to which are fastened the curtains *n* in the usual manner, as shown in Fig. 1. The outer ring *m'* of each pole is prevented from being displaced on the pole *g* by the pin or cotter *i*, so that the latter serves two purposes. To the inner curtain-ring *m''* of each pole is fastened the cord *h*, which passes over the loosely-pivoted bolts *f*. By a pull at one end of the cord *h*, Fig. 1, the two curtains *n* are drawn together, and by a pull at the other end they are drawn apart. The two curtains *n* of Fig. 1 are arranged on the two rear poles *g*, (shown in a ground plan in Fig. 2,) so that both can be moved by a single cord *h*. The front pole *g*, Fig. 2, holds also a curtain, and this is moved separately by a special cord *h*, which also passes over the bolts *f*.

If the whole window decoration is to be removed for the purpose of cleaning, all that is required is to simply take off the frame from the wall-hooks *c*. 70

Having thus described the invention, what is claimed, and desired to be secured by Letters Patent, is— 75

In a curtain-holder, the combination with the curtain-frame, of flat iron pieces secured to the frame and having a plurality of bends, wall-hooks for engagement with said iron pieces, curtain-poles inserted through slots in said iron pieces, curtain-rings on said poles, curtains secured to said rings, pins inserted through said iron pieces and engaging said curtain-poles and the outer of said curtain-rings, bolts journaled in said iron pieces, and cords secured to the inner curtain-rings and passing over said bolts, substantially as described and for the purpose set forth. 85

The foregoing specification signed at Cologne this 25th day of November, 1903. 90

HEINRICH ALBERTZ.

In presence of—

GUSTAV ELSNER,
WILHELM KÜPPERS.
